LOOSE LEAF BINDER

Filed July 30, 1932

FIG. 1

INVENTOR.

PAUL O. UNGER

BY

Benjamin Schlosser
ATTORNEY.

UNITED STATES PATENT OFFICE

PAUL O. UNGER, OF GLEN ELLYN, ILLINOIS, ASSIGNOR TO WILSON-JONES COMPANY, OF CHICAGO, ILLINOIS, A CORPORATION OF MASSACHUSETTS

LOOSE LEAF BINDER

Application filed July 30, 1932. Serial No. 626,919.

This invention relates particularly to a loose leaf binder of the catalog type, although it may be used with any style of post binder.

It is an object of this invention to provide a loose leaf binder of this type in which the alignment of the posts with the locking slide may be accomplished with less trouble than in the past. It is a further object of this invention to provide visible means for 10 guiding the heads of the posts into engagement with the locking bar. It is a further object of this invention to provide improved means for holding the posts in locked position and to give the post heads support in both 15 walls of the case. Other objects of this invention will become apparent upon reading the following specification taken in conjunction with the accompanying drawing in which

Figure 1 is a perspective view of a loose 20 leaf binder embodying my invention with parts broken away to facilitate illustration;

Figure 2 is a cross-sectional view illustrating the binding post and related structure;

Figure 3 is a fragmentary plan view of the 25 locking slide and related structure;

Figure 4 is a plan view of the locking slide with the top of the sheath broken away; and

Figure 5 is a longitudinal section through 30 the locking slide and sheath.

In the drawing the reference numerals 2 and 3 indicate a pair of covers connected by a back 4. The cover 2 carries a fabric loop 5 which extends the entire length of the binder and encloses a metal strip 6. A plurality of 35 tubular posts 7 are rigidly secured to metal strip 6, as indicated at 8. The upper portion of the tubular post 7 is reduced in diameter, as indicated at 9, and is provided with internal threads 10. A screw post 11 has its lower 40 end 12 threaded to engage with the threads 10 so that the height of the posts may be adjusted within certain limits. Since the maximum height of the posts depends upon the width of the back, it is obvious that if the 45 back were made extensible, or omitted altogether, that the posts could be made any desired height.

The binder is provided with a metal transfer bar 13 having a plurality of depending 50 sleeves 14 adapted to fit over the tubular posts

7. The transfer bar retains the uppermost sheets in place when the top cover is removed, and permits free access to any sheet filed in the binder without disturbing any other sheets. The transfer bar also serves to protect 55 the sheets from being caught on the screw-threaded portion 12 of the screw post 11.

The portion 15 of the screw post 11 immediately above the screw-threaded portion 12 is of substantially the same diameter as the lower portion of the tubular post 7 so that the sleeves 14 fit snugly. The screw post 11 is provided at its top with a neck 16 of reduced diameter and a button 17 of the same diameter as the portion 15. A pin 18 extends from the 60 top surface of the button 17.

The cover 3 of the binder is provided with a fabric loop 19, similar to the member 5, which encloses a metal sheath 20. The lower surface of the sheath 20 is notched, as indicated at 21, to accommodate the portion 15 of the screw post 11. The outer edge of the sheath 20 adjacent the notch 21 is cut away, as indicated at 22 so that the sheath may be 65 positioned by a horizontal sliding movement. The top of the sheath 20 is provided with a 70 narrow slot 23 adapted to receive the pin 18. The slot 23 is provided with a flared mouth 24 to facilitate guiding the pin 18 into the slot 23. The slot 23 fits the pin 18 snugly 75 and aids in preventing movement of the screw posts when the binder is closed.

The sheath 20 carries a locking slide 25 which is provided with a downturned handle 26 by which it may be operated. The locking slide has a slot 27 into which a portion 28 struck out from the sheath 20 fits to limit longitudinal movement of the slide in one direction. Movement of the slide in the other direction is limited by the downturned handle 26. The locking slide is provided with bayonet slots comprising a wide transverse portion 29 and a narrow longitudinal portion 30. The portion 29 is wide enough to receive the portion 15 of the screw post 11, but the portion 30 is adapted to fit the reduced portion 16 snugly. 80

The sheath 20 is deep enough to receive the 85 slide 25 and the button 17. A plurality of bosses 31 are struck down from the sheath to 90

retain the slide in position adjacent the bottom of the sheath so that the button 17 may be positioned without difficulty. The slide 25 is of substantially the same thickness as the height of the reduced neck portion 16 of the screw post 11 so that the button 17 and pin 18 always occupy the same relative positions with respect to the sheath 20. The pin 18 is of substantially the same height as the thickness of the top wall of the sheath 20 so that the top of the pin is substantially flush with the top of the sheath when the binder is in locked position.

The operation of the binder is as follows: 15 A plurality of sheets 32 are mounted on the transfer bar 13 which is then inverted and positioned over the posts of the binder. The tops of the posts are then screwed down until the tops of the portions 15 of the screw posts 20 are substantially flush with the top of the transfer bar 13. The sheath 20 is then moved into position over the transfer bar 13 so that the reduced neck portions 16 of the screw posts 11 are positioned in the slots 29 and the 25 pins 18 are snugly engaged by the slots 23. The locking slide 25 is then moved longitudinally so that the slots 30 snugly engage the reduced neck portions 16 of the screw posts. The engagement of the slide 25 with the reduced neck portions 16 forces the sheath 20 slightly downward so that the notches 21 snugly engage the portions 15 of the screw posts 11.

From the foregoing, it will be apparent 35 that each post 11 is securely held at three points of contact in my improved structure. The portion 15 contacts with the edges of the slot 21; the portion 16 contacts with the edges of the slot 30; and the portion 18 contacts with 40 the edges of the slot 23. These three separate points of contact constitute an exceptionally rigid connection between the post and the sheath 20 and prevent any relative movement therebetween when the binder is closed.

45 The slot 23 serves an additional purpose besides increasing the sturdiness of the connection between the sheath 20 and the posts. It enables the user to see the top of the posts so that the sheath may be more readily positioned. With my construction it is possible for the user to position the sheath 20 by snapping it down over the posts like a glove fastener or by sliding it horizontally. The top 55 of the pin 18 is substantially flush with the top of the sheath 20 so that none of the advantages of a non-protruding post are dispensed with and many advantages not heretofore deemed possible with a non-protruding post are attained.

60 Although I have described my invention in considerable detail, it will be understood that various structural details may be modified without departing from the spirit or scope of my invention. Accordingly, I do 65 not desire to be restricted to the exact details

described except as limited by the appended claims.

I claim:

1. In a loose leaf binder, a pair of covers, a tubular sheath secured to one of said covers, a metal strip secured to said second cover, a post carried by said strip, a button on said post adapted to fit within said sheath, a slot in the top surface of said sheath, and a pin extending from said button adapted to fit in said slot. 75

2. In a loose leaf binder, a headed post having a pin extending from the top thereof, and a tubular sheath having its bottom wall slotted to receive one portion of said post and its top wall slotted to receive said pin. 80

3. In a loose leaf binder, a headed post having a pin extending from the top thereof, a tubular sheath having opposite walls slotted to receive a portion of said post and said pin, and means in said sheath to retain said post in position. 85

4. In a loose leaf binder, a post provided with a button adjacent its upper end, a metal sheath slotted so as to receive said button, and a pin extending from the top of said button and fitting into a slot in the top wall of said sheath. 90

5. In a loose leaf binder, a post provided with a button adjacent its upper end, and a metal sheath having two adjacent walls slotted to receive said button, said sheath having a slot with a flared mouth in its top wall to facilitate alignment of said button with said first-mentioned slot. 100

6. In a loose leaf binder, a metal sheath carrying a locking slide, means to retain said slide in said sheath in spaced relationship to the top wall of said sheath, a post having a button adjacent one end thereof, said button being receivable in said sheath between said locking slide and said top wall, said top wall of said sheath being provided with a slot, and means on said post adapted to operate with said slot to facilitate positioning of said button. 105

7. In a loose leaf binder, a post provided with a reduced neck portion near its upper end, a button adjacent said reduced neck portion, and a pin extending from the top surface of said button, a tubular sheath notched to engage said post adjacent said reduced neck portion and to engage said pin, and a locking slide carried by said sheath, said slide being notched to engage said post at said reduced neck portion. 115

8. In a loose leaf binder, a pair of covers, a metal strip carried by one of said covers, a post secured to said strip, said post being provided with a reduced neck portion near its upper end, and a pin at the upper extremity of said post, a tubular sheath carried by said second cover, a plurality of interconnecting slots in said sheath adapted to receive said post, and means to maintain said 125 130

post at a predetermined height in relation to said sheath, whereby the uppermost end of said pin is retained substantially flush with the upper surface of said sheath.

5 In testimony whereof I have hereunto subscribed my name.

PAUL O. UNGER.
